FUSE CLIP CLAMP

Lewis Detch, 2133 Chalfant St., Pittsburgh, Pa.

Filed Dec. 19, 1957, Ser. No. 703,795

2 Claims. (Cl. 339—259)

The present invention relates to fuse clip clamps and refers more particularly to clamps of built up construction.

Fuse clips which have had long service lose some of their resiliency due to repeated heating and cooling. The clips may also be spread too far apart by negligent forcing of the fuse too far down in the clip. Poor mechanical contact between fuse and clip results in poor electrical conductivity between the two and causes the fuse to heat unduly and blow prematurely. Fuse clips are frequently very inconvenient to replace and consequently whole panels or boxes are replaced at substantial cost.

An object of the present invention is to provide a fuse clip clamp which may be applied over old or new clips by the fingers of an operator.

Another object is to provide a clamp having superior reinforcing action.

A further object is to provide a clamp having substantial heat sucking and heat dissipating properties, so that the fuse may operate for a longer time under conditions close to its calculated rating.

In accomplishing the objects of the present invention a fuse clip clamp is provided having a short inner flap and a longer outer flap located on each side of the clip, the flaps on each side of the clip being integral with a bottom member and forming therewith a J shape in cross section, the four flaps being connected together in a rectangular formation by transverse bars extending from one side to the other of the clip, and the flaps and bars, being unitary, preferably being stamped from a single sheet of metal. So much of the new construction is known, being disclosed in my copending application, Serial No. 549,390, filed November 28, 1955, and now abandoned.

The above described construction is both reinforced mechanically and rendered more absorptive of heat by a heavy copper pad located inside the J formation in each side of the clamp. This pad is preferably at least equal in height and width to the outer flap and may exceed the latter in height, and in case the outer flap is curved the pad is correspondingly curved. The pad is preferably riveted to the outer flap. The pad being in contact with the clip draws heat therefrom and both the clip and fuse are thus cooled and rendered more uniform in operation. Due to the cooling, over a given period of time fewer fuses will blow and the clip is thus subjected to fewer cycles of heating and cooling and the life of the clip is thus prolonged.

In a modified form of the invention, each pad is provided at its top inside surface with a smaller pad of less conductive material such as steel. As the clip and clamp are alternative electrical paths for the current, the steel being less conductive will cause more current to flow through the clip. The pad thus carrying a smaller current will be less heated and will be able to draw more heat from the clip and fuse.

In another modified form of the invention, the pad is formed with a recess extending across its length and

terminating short of its top and bottom. Air circulating in this recess cools both the pad and outer flap and increases the cooling capacity of the clamp.

The invention accordingly consists in the features of construction, combinations of elements and arrangements of parts which will be exemplified in the constructions hereinafter described. In the accompanying drawing, in which are shown three of the various possible illustrative embodiments of this invention:

10 Figure 1 is a perspective view of the invention embodied in a clamp for a ferrule type fuse, showing also the fuse clip and showing the fuse and block in fragment.

Figure 2, is a central vertical section through the clip and clamp of Figure 1, showing the fuse in end elevation.

Figure 3 is a corresponding view of a modified form of the invention.

Figure 4 is a corresponding view of a clip and clamp only of another modified form of the invention.

Referring now in detail to Figures 1 and 2, a fuse block 10 has mounted thereon a fuse clip 11 for a ferrule type fuse 12, all of the above being conventional. The clamp 13 has a chassis 14 which is a unitary body, preferably a stamping of Phosphor bronze spring sheet. Chassis 14 has the side rails 15 and end rails 16 defining a rectangular opening 17 through which the arms 11A of the clip 11 may pass. Integral with side rails 15 are the upstanding inner flaps 18 and longer outer flaps 19, also upstanding, the flaps 18, 19 extending substantially the full length of the side rails 15. The two flaps 18, 19 integral with a side rail 15 thus form with said rail a J shape. The flaps 18, 19 are resilient and bear inwardly against the arms 11A of the clip 11, the flaps 18 being in contact with the arms 11A and the flaps 19 bearing against the arms 11A through the pads 20.

35 Said pads 20 are relatively thick blocks of metal, preferably a high thermal conductive metal such as copper. The pads 20 are located between the flaps 18, 19, extending the full length of the flaps, and also extending from the side rails 15 to above the flaps 19, and further 40 being curved so as to contact near their tops the arms 11A of the clip 11. Rivets 21 hold the pads 20 in contact with the flaps 19 and the thermal conductive relation of pad and flap may be enhanced by solder 22 uniting the two.

45 In operation, the clamp 13 may be easily pushed down over an empty clip 11 by the fingers of an operator, the clip entering the opening 17 as the clamp passes downwardly. The relation of clamp and clip will then be approximately as illustrated in Figures 1 and 2 except that the clamp will fit loosely on the clip. When the 50 fuse 12 is then forced into the clip the latter will be distended as illustrated. The high thermal conductive pads 20 are now in contact with the arms 11A, being resiliently maintained in such contact by the outer flaps 19. The inner flaps 18 are also in contact with arms 11A and with the pads 20. From the above it will be observed that the resilient flaps 18, 19 have to a limited extent gone solid with the massive interposed pads 20, forming thereby a large heat reservoir which will draw heat from the clip 11 and fuse 12 as the latter produces heat on moderate overload. It is important to remember however that some resilience remains in the structure. For instance, a small upwardly diminishing tapered space 23 remains between arms 11A and the lower part of the inner flaps 18. Even in the absence of such space, the flaps 18 can slide on pads 20 and pads 20 can move relative to rails 15 albeit slightly, so that the clamp retains adaptability to clips and fuses of slightly differing dimensions such as result from design differences and manufacturing tolerances. The solder 22 is optional,

65 the use thereof increasing heat transfer from pad 20 to flap 19 for more efficient dissipation to the surrounding

air, while neutralizing the resilient properties of so much of flap 19 as is united to the massive pad 20. In the absence of solder a less efficient heat transfer is had and the full resilience of flap 19 is retained.

A further advantage of the within invention is that the heat sucking pads 20 are interposed between the flaps 18, 19 so as almost to fill the space therebetween and when the clamp is in operation the short inner flaps 18 bear against pads 20 and the latter bear against flaps 19 so that the resilient force of flaps 19 is in part added to the flaps 18 in their important function of reinforcing the base portions of the arms 11A.

In Figure 3 is illustrated a clamp 30 identical to clamp 13 except as noted hereafter. Clamp 30 has no solder between the outer flaps 39 and pad 40, the two being connected merely by the rivet 41. A small tapered space 42 exists between the bottom of pad 40 and flap 39. The absence of a similar space between inner flaps 38 and pad 40 should be considered as illustrative of the different fit between clamps of identical dimensions on clips and fuses of slightly different dimensions, rather than as illustrating a difference in function of the clamp. It has been noted in respect of clamp 13, Figures 1 and 2, that the flaps still retain the ability to move relative to the rail and that the inner flap may still slide on the pad. It is additionally true in clamp 30 that flaps 39 retain their full resiliency. Therefore clamp 30 despite an apparent difference in the illustration is effective like clamp 13 to reinforce the short inner flaps 38 with the resilient action of the outer flaps 39 acting over the interposed pads 40.

The pads 40 are of high thermal conductive metal such as copper, and have small pads 42 extending along their length at their top, the pads 42 being of steel or some metal of comparatively low electrical conductivity. The pads 42 thus constitute an electrical resistance which will limit the flow of current through pads 40 and cause the current to flow rather through the clip 31. As the clip 31 was designed to carry the full current, the resistance in pads 42 will not produce any substantial heat. However as the current has been confined substantially entirely to clip 31, the clamp 30 will remain cooler than if it had carried a current, and will thus be able to draw more heat from the clip 31 and fuse 32.

In Figure 4 is illustrated another modified form of the invention. A clip 50 for a knife blade fuse, not shown, is loosely engaged by the clamp 51, the looseness of the engagement being due to the absence of the fuse. Clamp 51 comprises a chassis 52 which is a unitary body comprising side rails 53, end rails 54, and inner flaps 55 and outer rails 56 extending upwardly from side rails 53 and constituting with the latter a J shape. The side and end rails define a rectangular opening 57 by means of which the clamp is applied to the clip from above. The relatively heavy pads 58 extend the length of the side rails 53, as do the inner and outer flaps 55, 56. The pads 58 are of high thermal conductive metal such as copper, and are in contact with the clip 50 and with the outer flaps 56, further being connected to the latter by the rivets 59. Pads 58 are formed with the

ventilating recesses 60 extending throughout their length and terminating short of the top and bottom of said pads 58. As the recesses 60 are thus open to the atmosphere at each end of the clamp, as the pads 58 draw heat from the clip 50 the air in the recesses will become heated and will escape being replaced by cooler air, and the circulation of air thus produced will cool clamp 51 and enable it to draw more heat from clip 50.

It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting sense.

What is claimed is:

1. A fuse clip clamp comprising, in combination, side rails and end rails connected together and defining a rectangular opening for a fuse clip, each side rail having integral therewith a resilient inner flap and a resilient outer flap, said flaps extending upwardly from each side rail, said inner flaps in operation being adapted to resiliently bear inwardly against the fuse clip, and a relatively thick pad of metal located between each inner flap and the respective outer flap and maintained in contact with the clip by the respective outer flap, each pad and its respective outer flap thereby constituting a heat reservoir to draw heat from the fuse clip while reinforcing the same mechanically.
2. In a clamp for a fuse clip, a chassis of unitary construction comprising side and end rails connected together and defining a substantially rectangular opening for a fuse clip, each side rail comprising integrally an inner resilient flap and an outer resilient flap, said flaps extending upwardly from said rail, said inner flaps in operation being adapted to bear inwardly against the fuse clip, and a comparatively thick pad of metal located between each inner flap and the respective outer flap, and adapted to be maintained in resilient contact with the fuse clip by said adjacent outer flap, to thereby draw heat from the fuse clip, said pad further substantially filling the space between the respective adjacent inner and outer flaps and adding part of the resilient force of the respective outer flap to the respective inner flap in the bearing of the latter against the fuse clip.
